BOTTLE STOPPER

George A. Kimber, Chicago, Ill.

Application February 6, 1937, Serial No. 124,410

7 Claims. (Cl. 215—52)

This invention relates to bottle stoppers, and particularly to stoppers of the composite expanding type.

One object of the present invention is to provide a bottle stopper of novel construction and arrangement of elements, particularly designed for nursing and like bottles, which is simple, inexpensive, efficient in its operation, and which may be readily and conveniently manipulated to facilitate the insertion into the neck of a bottle, and its convenient removal therefrom.

Another object of the invention is to provide a stopper of novel construction adapted to cooperate with a bottle neck in a manner, normally, to effectually seal the opening in the bottle neck and resist accidental or unintentional removal of the stopper therefrom.

Another object of the invention is to provide a stopper of the expanding type having portions whereby the stopper may be effectually employed for use in the neck openings of bottles having a wide range in the size of such openings.

Another object of the invention is to provide a stopper which may be sterilized, and which may be conveniently and hygienically handled immediately after such treatment.

A further object of the invention is to provide a novel construction and arrangement wherein an efficient sealing engagement of the stopper with the neck portion of the bottle is assured.

A still further object of the invention is to improve devices of the character described in sundry details hereinafter referred to and particularly pointed out in the appended claims.

One embodiment of the invention is shown for illustrative purposes in the accompanying drawing, in which,

Fig. 1 is an elevational view of a composite expanding type bottle stopper embodying features of the present invention, and illustrating the manner of inserting my improved stopper into the neck of a bottle;

Fig. 2 is a sectional elevational view of my improved stopper and a bottle neck illustrating the stopper therein in sealing position;

Fig. 3 is an elevational view of my improved stopper illustrating its adaptation to a bottle having a neck opening of substantially less diameter than those shown in Figs. 1 and 2; and

Fig. 4 is a sectional elevational view of a stopper of slightly different construction than those shown in Figs. 1, 2 and 3.

As previously stated, this invention relates to bottle stoppers of the composite type, and is an improvement on the structure disclosed in my co-

pending application for Bottle stopper, filed February 26, 1936, Serial No. 65,848.

Referring to Figs. 1 to 3 of the drawing, the present invention contemplates a body member indicated, as a whole by the numeral 5, and shown, in the present instance, as comprising a pair of preferably elongated cup-like elements 6 and 7 formed of resilient material, such for example, as rubber or the like, the elements 6 and 7 having their open end portions positioned adjacent each other in a manner to form an elongated chamber 8 within the body member 5.

As noted in the drawing, the elements 6 and 7 are provided, adjacent their abutting end portions intermediate and substantially midway between the ends of the member 5, with outwardly or laterally extending flanges 9 and 11, respectively, the flanges as shown in Fig. 2 being positioned between and secured together by ring-like plates 12 and 13 positioned on opposite sides of the flanges and secured in relation thereto by means of a downwardly and inwardly extending edge portion 14 of the plate 13.

It will be noted that the elements 6 and 7 of the present invention are of substantially different diameters, and may be effectually employed for use in the neck openings of bottles having a wide range in the size of such openings. Positioned within the chamber 8, formed by the cup-like members 6 and 7, is an elongated substantially cylindrical actuator 15, by which one or another of the elements 6 and 7 may be elongated, as shown in Fig. 1. For example, to facilitate the positioning of the stopper within the neck 16 of a bottle either of the elements 6 or 7 may be elongated, it being understood that in manipulating the device of the present invention to elongate one of the elements, shown in Fig. 1 as the element 6, the other element 7 will be compressed or collapsed as shown in Fig. 1. It will be noted also that the relation of the laterally extending flanges 9 and 11 together with the fastening plates 12 and 13 provide means against which the middle and forefingers of one's hand may be placed, while one or another of the elements 6 or 7 may be pressed inwardly by the thumb of the user.

If desired, one or the other of the elements 6 or 7, preferably 7, may be provided with an aperture 17, shown in Figs. 2 and 4, as positioned in the outer end of the element 7, and the actuator 15 may be provided with a notch or groove 18 adjacent the aperture 17 and shown, in the present instance, as formed in one end of the actuator in a manner to provide a vent for the breaking of any vacuum occurring within the chamber 8,

which might otherwise cause a collapse of the elements 6 and 7, and thereby interfere with the efficient operation of the device or relieve any pressure.

5. Fig. 4 illustrates a structure substantially like that described with reference to Figs. 1, 2 and 3 of the drawing, except that in lieu of the plates 12 and 13 for securing the flanges 9 and 11 together, a ring 13a of suitable material, such for example, 10 as hard or stiff rubber or the like, may be vulcanized to the flanges 9 and 11 in a manner to secure them together, and to provide a substantially rigid flange adjacent the midportion of the member 5 to assist in the elongating of one or another 15 of the elements 6 or 7 to facilitate their being positioned in the neck of a bottle.

It will be observed from the foregoing description that the present invention provides a novel construction and arrangement in bottle stoppers 20 of the expanding type, whereby the stopper may be employed for use with bottles having a wide range in size of openings, and that the present invention provides a stopper which may be boiled or otherwise sterilized to render it hygienic, 25 and which may be conveniently handled for insertion in the neck of a bottle.

The present invention is particularly well adapted for use in bottles used for feeding purposes, as, for example, in nursing bottles, or in 30 other instances wherein it is found desirable to prepare a quantity of liquid food in a number of bottles, and after sterilizing the stoppers, they may be placed in the respective bottles, and the bottles set aside in a refrigerator or the like, 35 from which the individual bottles may be subsequently and conveniently obtained for consumption of the food.

Obviously, the present invention is not limited to the precise construction and arrangement 40 shown and described, as the same may be variously modified without departing from the spirit and scope of the invention as set forth in the appended claims.

What I claim as new and desire to secure by 45 Letters Patent is:

1. In a bottle stopper, the combination of a hollow body member of resilient material, a substantially rigid laterally extending flange on said member adjacent its mid-portion, and relatively 50 movable means in the said body member for elongating a portion thereof at one side of said flange.

2. In a bottle stopper, the combination of a hollow body member of resilient material, a laterally extending flange on said member adjacent its mid-portion, and relatively movable means 55 in said body for elongating portions thereof at opposite sides of said flange.

3. In a bottle stopper, the combination of a hollow body member of resilient material, a laterally extending substantially rigid flange on said member adjacent its mid-portion, an elongated relatively movable actuator in said body member for elongating the portions thereof at opposite sides of said flange. 5

4. In a bottle stopper, the combination of an elongated hollow body member of resilient material, a laterally extending substantially rigid flange on said member intermediate its end portions, an elongated relatively movable actuator in said body member and engageable with the inner end portions thereof for elongating the portions of said body member at opposite sides 10 of said flange.

5. In a bottle stopper, the combination of a body member comprising a pair of cup-like elements formed of resilient material and having their open end portions positioned adjacent each other to form a chamber in said member, laterally extending flanges on the respective abutting end portions of said elements, means securing 20 said flanges together, and an actuator in said chamber for elongating the respective elements 25 at opposite sides of said flanges.

6. In a bottle stopper, the combination of a body member comprising a pair of elongated cup-like elements formed of resilient material and having their open end portions positioned adjacent each other to form an elongated chamber in said member, laterally extending flanges on the respective abutting end portions of said elements, a substantially rigid ring-like fastener 30 for securing said flanges together, and an elongated relatively movable member in said chamber engageable with the end portions thereof for further elongating the respective elements at opposite sides of said flanges. 35

7. In a bottle stopper, the combination of a body member comprising a pair of elongated cup-like elements formed of resilient material and having their open end portions positioned adjacent each other to form an elongated chamber in said member, one of said elements having an 40 aperture formed therein communicating with said chamber, laterally extending flanges on the respective abutting end portions of said elements, substantially rigid means securing said flanges together, and an elongated relatively 45 movable actuator in said chamber engageable with the end portions thereof for further elongating the respective elements at opposite sides of said flanges, said actuator having a recess 50 formed therein adjacent said aperture. 55

GEORGE A. KIMBER.
